UNITED STATES PATENT OFFICE.

CHARLES L. HOLT, OF LAWRENCE, MASSACHUSETTS, ASSIGNOR TO HOLT ROOF CONNECTION CO., OF LAWRENCE, MASSACHUSETTS, A CORPORATION OF MASSACHUSETTS.

ROOF CONNECTION FOR DRAIN-PIPES.

1,252,573.

Specification of Letters Patent.

Patented Jan. 8, 1918.

Application filed October 8, 1915. Serial No. 54,850.

To all whom it may concern:

Be it known that I, CHARLES L. HOLT, a citizen of the United States, residing at Lawrence, in the county of Essex and State of Massachusetts, have invented an Improvement in Roof Connections for Drain-Pipes, of which the following is a specification.

This invention relates to certain improvements in roof-connections of the type shown in my prior Patent #1,059,671, dated April 22, 1913, in which a drain pipe is connected to the roof of a building; which is flat or inwardly inclined, to conduct rain water therefrom, down through the interior of the building.

In the device of my prior patent, the primary purpose was to provide a means whereby the joint between the roof flashing and the pipe would not be subjected to strain or impaired in case of relative movement of the roof and drain pipe, and, while this device is entirely suitable, so far as I am aware, for buildings in which the roof is of wood, or is of ordinary thickness, it cannot be conveniently employed, and frequently cannot be employed at all in buildings having roofs which are constructed of cement, particularly if the roof is of considerable thickness, or in cases where the drain pipe is so located that access thereto from above the roof, only, is possible, when the roof connection is to be made.

In my said prior device a slip joint is employed in the drain pipe in close proximity to the roof. This arrangement is objected to in some cities where calked joints, only, are permitted in a drain pipe.

The primary object of my present invention is to provide a form of roof connection which possesses the features of advantage of the device of my prior patent, and which is especially adapted for use in connection with cement roofs, or roofs of considerable thickness, and is adapted for use in those special instances where the entire connection to a previously installed drain pipe must be made from above the roof.

A further object of my invention is to provide a construction which will obviate the employment of a slip joint in the drain pipe.

I accomplish these objects, primarily, by providing a roof fitting with means whereby, when it is once lowered into the roof open-

ing, it will become automatically connected with the roof, without regard to the depth of the opening, and further, by locating the slip-joint connection between the drain pipe and the fitting, instead of in the pipe itself, and by arranging the parts so that the connections which must be made at the time of installation may be made from above the roof.

For a more complete understanding of my invention, reference is made to the accompanying drawing, in which;

Figure 1 is a vertical, central sectional view on the line 1-1 of Fig. 2, of a roof fitting embodying my invention.

Fig. 2 is a plan view thereof, partly cut away.

Fig. 3 is a vertical sectional view, at the line 3-3 of Fig. 2.

Fig. 4 is a detail sectional view, on an enlarged scale, taken at the line 4-4 of Fig. 2.

Fig. 5 is a side elevation of a portion of the fitting, illustrating one of the locking devices.

Fig. 6 is a detail view of a form of locking device which I employ.

Fig. 7 is a plan view of a roof casing which I preferably employ.

Fig. 8 is a detail vertical sectional view and modified form of fitting.

In the drawing, 1 indicates the concrete roof of a building which may be of any thickness, the particular thickness shown, with relation to the fitting, being immaterial. While an opening for the fitting may be formed through the roof, after the roof has been laid, in practice, it is generally known exactly where the drain pipe is to be connected to the roof before the roof is laid, so that, preferably, at the time it is laid, a form is placed in the position which the fitting is to occupy, and cast in the cement in this position. To this end, I preferably provide a sheet metal casing 2, which is shaped to receive the fitting thereafter to be installed, and which extends from the top to the bottom of the roof, so as to provide an opening therethrough, said casing becoming a permanent part of the structure. It will, however, be obvious that a pattern may be cast in the cement, which may be removed, and which will serve practically the same purpose as the casing.

According to my invention, I provide a roof fitting 3 which is made of cast iron, or other suitable metal, and, in the preferred form of my invention, is made somewhat 5 in the form of a circular bowl, the rim of which is provided with a laterally projecting flange 4, which is adapted to support the fitting upon the surface of the roof. A central passageway is formed through the 10 bottom of the bowl portion of the fitting, and integrally formed pipe or tubular projections 5, 6, constitute the walls of said passageway, and extend above and below the bottom of the bowl, the projection 5, 15 above the bottom of the bowl, terminating approximately midway of the height of the bowl, and the projection 6, below it, extending down far enough to provide a packing-receiving recess, the bottom of which is 20 formed by an inwardly projecting shoulder 7, from the inner edge of which a tubular projection 8 depends. The passageway through the fitting is thus of substantially greater diameter above the shoulder 7, than 25 below it. A sleeve 9, which is preferably of brass or copper, is arranged within the passageway of the fitting, and normally extends from the upper end of the tubular projection 5 to a point approximately midway 30 of the lower tubular projection 8, the external diameter of said sleeve being slightly less than the internal diameter of said projection 8, so that the sleeve may move readily therein, and an annular recess will be 35 provided between the sleeve and the fitting, above the shoulder 7.

A pair of lead packing rings 10, which are filled with graphite grease, or the like, are placed, one on the other, in this annular 40 space, so that they rest on the shoulder 7, and an iron ring 11 is then clamped down on said rings, by a gland 12, which is forced down by means of bolts 13, which pass through the flange of the gland and are 45 screwed into the upper end of the upwardly extending tubular projection 5. A lead washer 14 is preferably placed between the projection 5 and the flange, and the parts are so arranged that, when the flange of the 50 gland ring is firmly clamped against the washer 14, the lead packing rings 10 will be sufficiently compressed to make a watertight joint between the sleeve and fitting, and yet permit the sleeve to slide to a limited extent 55 therein, without disturbing the watertight joint which has been formed. The gland is preferably of somewhat less thickness than the space in which it is located, while its flange aperture fits on the sleeve as closely 60 as practicable, and the spaces between the gland and sleeve and between the gland and fitting are preferably filled with a suitable packing 65, of permanent nature, such as "graphite-grease", and which will permit the sleeve to slide within the gland, and

also exclude water from entering such spaces. The upper end portion of the sleeve 9 is provided with a series of apertures or recesses 9' for a purpose which will hereafter appear. 70

A pair of ribs 15 are integrally formed with the fitting, and are arranged in parallelism at opposite sides of the bowl portion, so that they depend from the flange 4, in as close proximity to the side walls of the fitting as practicable, as shown in Figs. 2 and 75 5. Two pairs of dogs 16 are pivoted on the inner or adjacent sides of said ribs, one dog being located at the end of each rib and each being arranged to swing outwardly from 80 the sides of the fitting, by the action of gravity, and, to make this action more positive, springs 17 are connected thereto in suitable positions, stop lugs, as 30, being arranged to limit the outward swinging movement of 85 said dogs.

In practice, the drain pipe 18 will have been placed in position, so that it will terminate a short distance from the under side of the roof, as indicated in Fig. 1, and when 90 the connection with the roof is to be made, a length of iron pipe 19 will be cut off to a suitable length, and lowered through the roof opening, so that it will seat in the hub of the pipe 18, and then the usual calked 95 lead joint will be formed between said pipes 18 and 19. If the sheet metal frame 2 has been previously cast into the roof, as shown in Fig. 1, notches or indentations 2' will be formed in the sides thereof, in position to 100 be engaged by the dogs 16, respectively, as indicated in Fig. 6. The fitting will then be lowered into the opening, so that its flange 4 will rest on the upper side of the roof. The dogs 16 are arranged so that their end 105 portions are normally held to project beyond the ends of the lugs 15, and, as the casing 2 is made just large enough to receive the fitting, said dogs will be pressed inward, as the fitting is lowered. The indentations 110 or notches 2' in the casing, are so located that, when the fitting is supported in the casing by its flange 4, the dogs will engage the casing in said notches 2', as illustrated in Fig. 6, locking the fitting against upward 115 movement therein. As shown in Figs. 1 to 4, the internal diameter of the sleeve 9 is substantially greater than the external diameter of the pipe 19, and said pipe 19 is made of such a length and is so located that, 120 when the fitting is lowered into place, its sleeve 9 will be passed onto the pipe 19, which latter will be cut to such length that its upper end will be flush with the upper end of the sleeve, when the fitting is in position, and an annular space will be provided 125 between the outer walls of the iron pipe and the inner walls of the sleeve. The upper ends of the iron pipe and sleeve are then connected by a calked lead joint, to form 130

which, the bottom of this annular space is first closed by any suitable means, as by forcing oakum or other suitable packing into the same, or by forcing a spring ring 20 down into the space, as indicated in Fig. 1, after which, molten lead 21 is poured into said space, which is filled to the level of the upper ends of the pipe and sleeve. At the same time, the molten lead will flow into the recesses 9', which have been formed in the upper end of the sleeve. The lead, when cool, is then forced into the space and adjoining recesses by the well-known method of calking, so that a rigid, water-tight joint 15 is formed between the pipe and the sleeve.

The usual sheet copper flashing 22 is placed on the flange 4, and extends down onto the roof, and is connected to the flange by means of a ring 23, which is securely 20 clamped on the upper side of the flashing by bolts 24, which are passed therethrough and screwed into the flange 4. Said ring 23 is provided with a flange, or rib 23', on its inner edge, which acts as a "gravel stop", 25 tar and gravel being subsequently laid on the roof to the level of the edge of this flange, as indicated in Fig. 1.

The sleeve 9 is of such length, and so arranged at the time of installation, that it extends several inches both above and below the packing rings 10. In case, therefore, of relative movement of the iron pipe and the roof, due, for example, to the expansion of the pipe or the sinking of the roof, the sleeve 35 9 will be caused to slide within the fitting, in contact with the packing 10, without impairing the tightness of the connection between the pipe and the fitting. In case the sleeve should not slide readily in the surrounding packing, no strain will be placed 40 on the joint between the flashing and fitting, as the fitting is locked against upward movement with relation to the roof, by the dogs 16, while the flange 4 prevents any 45 downward movement relative thereto.

A strainer 25 is preferably secured on the upper side of the gland ring 12, by means of bolts, which pass through ears 26 projecting from the edge of its flange, the strainer being of such size and so held that its inner 50 edge is at a short distance beyond the edge of the flange of the gland, as indicated in Figs. 1 and 2.

With the above-described construction of 55 fitting, an annular space is provided in the bowl about the upwardly projecting pipe 5, and the gland-ring-flange thereon. In case of heavy rainfall, the gravel on an ordinary tar-and-gravel roof is frequently washed 60 into the drain pipe, so that the traps are choked, and damage is caused. With the above-described construction, however, gravel which is washed over the gravel-stop 28' will be retained in the bowl of the fitting 5, until it is practically filled. As the

amount of gravel which would be likely to be washed into the bowl would not more than fill the same, the possibility of difficulty on account of gravel being washed into the drain pipe, is practically obviated. 70 Accumulations in the bowl may be readily removed.

As shown in the drawing, the fitting 3 is slightly smaller than the space provided to receive it in the casing 2, so that it fits 75 loosely therein. This arrangement is advantageous in that it permits lateral expansion of the fitting, without danger of breakage.

To explain the advantages of this feature 80 more fully, the provision of a sheet metal casing, which is cast in the cement of the roof, at the time the cement is placed in position, and into which the fitting may later be placed, is advantageous over the 85 method of casting the fitting directly into the cement, not only on account of considerations of convenience and expediency, which are many, but also on account of the fact that if the cast metal fitting were embedded 90 directly in the cement, it would be likely to cause damage, or be damaged on account of the different coefficients of expansion of iron and of cement.

With the above-described arrangement, 95 ample provision is made for the expansion and contraction of the fitting, independently of the cement in which it is suspended. By providing a space of substantial width between the casing and fitting, provision is 100 also made for lateral adjustment of the fitting, when necessary, to bring it into alignment with the pipe.

In Fig. 8 a somewhat modified form of fitting is illustrated, the bowl-shaped formation being omitted, this arrangement being preferable where the fitting is used for a vent pipe connection, instead of for a drain pipe. With this exception, the construction is practically the same as that already described, the fitting 27 being provided with side walls which extend directly from the level of the gland ring flange 28 to the level of the edge-flange 29 thereof. 105

In Fig. 8, the casing 2 is not shown and 110 the dog 16' is shown as directly engaging the cement of the roof, which is ordinarily sufficiently rough to serve the same function as the indentations 2' in the casing.

With the above-described construction, it 115 will be apparent that all the connections may be made, including the joint between the pipes 18 and 19, if necessary, from above the roof, so that it will be immaterial how thick the roof may be. It will be further 120 observed that the provision of slip-joints at any point below that where the water enters the pipe, is avoided.

I claim:—

1. A roof connection for drain pipes com- 130

prising a roof-fitting having a tubular passageway therethrough, means on said fitting to engage the roof to hold the same against movement relative thereto, either up or down, a sleeve in said passageway having a slip-joint connection with the walls thereof, and a drain pipe insertible in said sleeve, and adapted to receive a packing between its exterior and the interior of the sleeve, to form a rigid water-tight joint therebetween.

2. A roof connection for drain pipes comprising a roof-fitting having a tubular passageway therethrough, means to engage the roof to hold said fitting against movement relative thereto, either up or down, a sleeve disposed in said passageway and having a slip-joint connection with the walls thereof, a drain pipe extending into said sleeve from its lower end and of substantially less external diameter than the internal diameter of the sleeve, to provide an annular recess therebetween, and a soft metal packing in said recess, to form a rigid, water-tight joint between the sleeve and pipe.

3. A roof connection for drain pipes comprising a roof-fitting having a tubular passageway therethrough, means to engage the roof to hold said fitting against movement relative thereto, either up or down, a sleeve disposed in said passageway and having a slip-joint connection with the walls thereof, a drain pipe extending into said sleeve from its lower end, and terminating at its upper end adjacent the level of the upper end of the sleeve, said pipe being of substantially less external diameter than the internal diameter of the sleeve, to provide an annular recess therebetween, and said sleeve having internal recesses at its upper end opening into said annular recess, and a soft metal packing forced into the upper end portion of said annular recess, and the recesses of the sleeve, to provide a rigid, water-tight connection between said sleeve and pipe.

4. A roof connection for pipes comprising a roof-fitting having a passageway therethrough, and having a laterally projecting flange at its upper end to support the same in a roof-opening, locking means on said fitting below said flange movable with relation to the fitting to permit the fitting to be lowered into the roof-opening, and to engage the sides of such opening to lock the fitting against upward movement therein, and a pipe having a yieldable connection with the fitting.

5. A roof connection for drain pipes comprising a roof-fitting having a passageway therethrough, a supporting flange projecting laterally therefrom to support the fitting in a roof-opening, a pair of dogs on the fitting automatically movable to permit the fitting to be lowered into the roof-opening, and to engage the sides of such opening, to

prevent upward movement thereof, and a pipe having a yieldable connection with the fitting.

6. A roof-fitting for pipes having a passageway therethrough, and a laterally projecting flange for supporting the same in a roof-opening, locking devices on the exterior of the fitting beneath the flange movable to permit downward movement of the fitting in the roof-opening and normally actuated to engage the walls of such opening to prevent upward movement therein, a pipe, and expansion joint-connecting means between said pipe and fitting.

7. A roof-fitting for pipes having a laterally projecting flange to support the same in a roof opening, and having a tubular passageway therethrough, a drain pipe having a slip-joint connection with the fitting, a pair of lugs on the outer side of the fitting at opposite sides thereof, and beneath said flange, and a dog pivoted on each lug in oppositely disposed positions and normally actuated to engage opposite sides of the roof opening to hold the fitting against upward movement therein and arranged to swing upwardly to permit the fitting to be lowered in the roof opening.

8. A roof connection for drain pipes comprising a fitting adapted and arranged to be held in a roof against up and down movement relative thereto and having a tubular passageway therethrough, a sleeve in said passageway having a slip-joint connection with the walls thereof, a drain-pipe disposed in said sleeve with its upper end terminating at approximately the level of the upper end thereof, and a calk joint between the respective exterior and interior upper end-portions of said pipe and sleeve, to form a rigid, water-tight connection therebetween.

9. In combination with a concrete roof, a casing embedded therein and opening at its top to the upper side of the roof and at its bottom to the under side thereof, a roof-fitting loosely-fitted in said casing and having means to hold the same therein against movement either up or down, and a drain pipe having a yieldable connection with said fitting.

10. In combination with a concrete roof, a bowl-shaped outer casing embedded in the roof and opening at its top to the upper side of the roof and at its bottom to the under side thereof, a similarly-shaped roof-fitting located in said casing and having an edge flange for supporting it in said casing and locking-means for holding it against removal therefrom, and a drain pipe having a yieldable connection with said fitting.

11. In combination with a concrete roof, a casing embedded therein and opening at its top to the upper side of the roof and at its bottom to the under side thereof, a metal roof-fitting supported in said casing and

arranged for lateral expansion and adjustment therein, means to hold said fitting against either up or down movement with relation to the roof, and a drain pipe having 5 a yieldable connection with said fitting.

12. In combination with a concrete roof having an opening therethrough, a fitting having an edge flange resting on the roof to suspend the same therein, a flashing plate 10 on said flange and extending onto the roof, a ring having an upwardly extending lip to form a gravel stop, means to clamp said ring on said plate and to clamp the plate on said flange, means to hold said fitting against upward movement in said opening, and a drain 15 pipe having a yieldable connection with said fitting.

13. A roof connection comprising a bowl-shaped fitting held in the roof against relative up or down movement and having a water-tight connection between the roof surface and its rim and an outlet passage leading from its bottom, a tubular projection surrounding said passage and extending upwardly from the bottom of the fitting, to provide a gravel catch-basin thereabout, and 20

a drain pipe having a yieldable connection with said outlet passage.

14. A roof connection comprising a bowl-shaped fitting held in the roof against relative up or down movement and having a watertight connection between the roof surface and its rim and an outlet passage leading from its bottom, a tubular projection surrounding said passage and extending upwardly from the bottom of the fitting, to provide a gravel-catch basin thereabout, a drain pipe extending upward through said outlet passage to points adjacent the upper end of said tubular projection, providing 35 an annular space therebetween, a packing in said space and a gland ring extending into said space and having a flange extending over said tubular projection and clamping bolts extending through said flange and 40 into said projection, to force the gland against the packing.

In testimony whereof, I have signed my name to this specification.

CHARLES L. HOLT.
